UNITED STATES PATENT OFFICE.

ELLWOOD E. HOPKINS, OF PHILADELPHIA, PENNSYLVANIA; CORA E. HOPKINS EXECUTRIX
OF SAID ELLWOOD E. HOPKINS, DECEASED.

COMBINED PENCIL HOLDER AND SHARPENER.

No. 895,019.

Specification of Letters Patent.

Patented Aug. 4, 1908.

Application filed February 5, 1908. Serial No. 414,342.

To all whom it may concern:

Be it known that I, ELLWOOD E. HOPKINS, of Philadelphia, in the county of Philadelphia and State of Pennsylvania, have invented certain new and useful Improvements in a Combined Pencil Holder and Sharpener, whereof the following is a specification, reference being had to the accompanying drawings.

This invention relates to improvements in compound implements used mainly in preparing and protecting the points of pencils and its objects are:—First, to provide an implement adapted to be retained at all times in connection with a pencil, as when not in use on the pencil point it may be disposed on the other end. Second, to provide an implement including an integral sharpening means, effective in reducing the wood surrounding the lead core in ordinary pencils and combined with means whereby the chips and fragments removed are retained and prevented from soiling either the person or premises. Third, to provide an implement, comprising an eraser, an efficient point protector and a sharpener so combined as to occupy a limited space, said sharpener being provided with means adapted to act as a manicure instrument in the trimming and cleaning of finger nails, the whole being of attractive appearance.

These objects are attained by the novel design and combination of parts hereinafter fully described and shown in the accompanying drawings, forming part of this specification, and in which:—

Figure I, is a side elevation of the rubber tip eraser and its holder, drawn to an enlarged scale and partially in section. Fig. II, is a similar view of the sharpener. Fig. III, is a side elevation of the sharpener, showing the manicuring devices. Fig. IV, is a side elevation of the sleeve, connecting the sharpener to a pencil and acting as a protector. Fig. V, is a greatly enlarged cross section of the sharpener. Fig. VI, is a similar cross section, indicating a modified form of sharpener, having a detachable blade. Fig. VII, is a side elevation of the combined implement.

The invention comprises a hollow steel cone 1, having a short cylindrical sleeve 2, integral with it and a slotway 3, passing longitudinally through both parts; one of the slot sides is finished smoothly throughout,

while the other side is similarly smoothly finished through the sleeve portion, but the edge is pressed inwardly throughout the conical portion and shaped into a sharp bevel, forming in effect, a knife blade or cutter 4, 60 the edge of which is disposed in such manner as to engage with whatever may be inserted within the cone. That end of the sleeve 5, which engages with a pencil has a slot 6, which provides sufficient elasticity for the 65 admission of a pencil within and maintains a pressure upon it in order to prevent accidental withdrawal, but not enough to hinder removal when desired, or impede the operation of revolving the pencil within the sleeve 70 in the process of sharpening it. The opposite end of the sleeve 5, is enlarged, as at 7, and is so made as to receive the cylindrical end of the sharpener 2, which is adapted to be tightly sprung into it and thereby retained normally, the slotway 3, being compressed by being forced into the sleeve thereby causing a tensional contact; a depressed portion 13, of the sleeve 7, also acts as a key 75 within the slotway, preventing the sharpener 80 from turning in the sleeve; the outer surface of the enlarged part 7, of the sleeve is also preferably corrugated for convenience in handling and operating the implement with reference to a pencil. 85

A rubber tip eraser 8, is removably secured in the holder 9, which is provided with an elongated slot 10, allowing the sleeve to pass over and be retained upon the cylindrical portion 2, of the sharpener extending 90 from the sleeve 7, when the sharpener is connected therein; the body 2, is of proper diameter so as to closely fit the sharpener, but may be enlarged where it surrounds the knife to allow the chips to readily fall therefrom and be retained in said body. 95

In operation a pencil is inserted within the sleeve 5, pushed forward until it contacts with the knife blade 4, and then revolved in the proper direction by the fingers; this action causes a shaving to be removed from the pencil and if continued the wood covering will be removed from the lead to the extent desired, leaving a conical point. It is noticeable that the lead itself has a bearing 100 in the interior of the sharpener, so that it is not easily broken by the action of the knife. It is also noticeable that the chips are retained in the holder until such time as it may be convenient to dispose of the same, 105 110

thus preventing the annoyance of chips and dirt in sharpening pencils.

From an inspection of the drawings it will be evident that all parts are made readily interchangeable, particularly the sharpener, which, when dull or worn by repeated use, may be discarded and a new sharpener easily inserted and that this can be done by inexperienced persons at a trifling expense.

10 In the modification shown in Fig. VI, is indicated a form of sharpener having a knife 15, inserted in a reentrantly turned portion 16, of the sharpener 2, said blade being held securely but solely by the clamp friction of 15 the contacting sides and readily removable when desired. The absence of all screws, solder or other holding means is evident from inspection, the blades being merely slipped into position, the sharpeners being 20 made in both cases from drawn sheet steel and formed from a single piece by the use of suitably constructed dies and proper power presses.

Referring to the manicure features of the 25 implement, the sharply cut recess 11, transverse of the sharpener and formed close to the sleeve 7, when the same is positioned on the sharpener, provides a cutter for trimming the nails, which can be used with perfect safety, no danger from inadvertent cuts being possible, while an effective trimming device is attained, leaving the nails in a smooth and satisfactory condition; not only can any preferred shape be obtained but the 35 edges of the nails are rounded and smoothed in a manner not possible to attain with a knife.

At the extreme front end of the sharpener is formed a projection 12, of the proper size 40 and shape to remove accumulations from beneath the nails and without injury to the cuticle. A nail file is also provided on a flattened portion 17, on the conical portion 1, of the sharpener 2.

45 The convenience of the combination is thought to be manifest.

Having thus described my invention, what I claim as new and desire to secure by Letters Patent of the United States, is:—

50 1. In a combined pencil holder and sharpener, the combination of a sleeve; a cutter formed of a split tube having a slotway and frictionally retained in said sleeve; and a projection on said sleeve entering the slotway of

said split tube to prevent relative rotation of said tube and sleeve.

2. In a combined pencil holder and sharpener, the combination of a sleeve; a cutter formed of a split tube having a slotway and frictionally retained in said sleeve; a projection on said sleeve entering the slotway of 6 said split tube to prevent relative rotation of said tube and sleeve; and an eraser holder frictionally secured to the exterior of said cutter and forming a chip retaining receptacle.

3. In an instrument of the class described, the combination of a sleeve; a cutter formed of a split tube which is conical at one end and provided with an integral projection at its 7 apex, the outer surface of said conical portion being provided with transverse cuts forming a file, said cutter being frictionally retained in said sleeve.

4. In an instrument of the class described, 7 the combination of a sleeve; and a removable cutter formed of a split tube which is frictionally retained in said sleeve and is conical at one end and provided with an integral projection at its apex. 8

5. The combination of a pencil cutter having a tubular and a conical portion formed integrally of a single piece of metal and slotted along one side from point to base, one edge of the slot being sharpened throughout the extent of the conical portion of the cutter; a sleeve provided with a seat adapted to receive the tubular part of the cutter and retain it therein under compression; and a lug within the sleeve adapted to engage the slot 9 in said tubular portion, whereby the cutter is removably held within the sleeve, the engagement of the lug preventing rotative movement.

6. In an instrument of the class described, 9 the combination with a sleeve; of a removable cutter formed of a tube which is conical at one end, split throughout its entire length and frictionally and detachably retained in said sleeve; said tube being provided with an 1 aperture having its periphery a cutting edge.

In testimony whereof, I have hereunto signed my name, at Philadelphia, Pennsylvania, this third day of February, 1908.

ELIWOOD E. HOPKINS.
